UNITED STATES PATENT OFFICE.

FREDERICK K. VREELAND, OF MONTCLAIR, NEW JERSEY.

RECEIVING SYSTEM FOR RADIO TELEGRAPHY AND TELEPHONY.

Original application filed February 17, 1917, Serial No. 149,166, now Patent No. 1,407,103, dated February 21, 1922. Divided and this application filed January 21, 1922. Serial No. 530,816.

My invention relates to an improved receiving system for radio telegraphy or telephony whereby the efficiency and clarity of the reception is improved. The invention 5 has for its particular object the elimination of interference by strays or foreign impulses, whether emanating from other radio transmitters or produced by atmospheric or "static" disturbances. While the invention 10 is highly effective in excluding artificial radio oscillations of foreign frequencies, it is particularly adapted to the much more difficult function of preventing objectionable interference with the received signals by atmospheric or "static" strays. The difficulty 15 of successfully overcoming or preventing the disturbances due to atmospheric or "static" strays arises not only from the great intensity of such disturbances, but particularly 20 from the fact that they are not simple harmonic oscillations, but are usually strongly damped or aperiodic. Such damped impulses are capable of exciting oscillations in 25 a tuned resonant circuit, irrespective of its frequency, and therefore they cannot be eliminated by ordinary methods of tuning.

In my said Patent No. 1,407,103, of which the present application is a division, I have described a receiving system including a baffle 30 circuit or circuits in combination with intensity selectors which is highly effective in eliminating the effects of stray impulses on the receiving system. In that patent I described, but did not specifically claim, 35 means for preventing the setting up and transmission of detrimental shock oscillations in the receiving system. The invention claimed herein has for its particular object the prevention of such shock oscillations and 40 their detrimental effect on the receiver.

In order that the invention may be better understood, attention is directed to the accompanying drawing forming a part of this specification.

Figure 1 shows an arrangement including a symmetrical baffle circuit and Figure 2 shows a similar arrangement including an asymmetrical baffle circuit.

As I have explained in the above mentioned patent, the difficulty in eliminating the effects of atmospheric strays on the receiver is due largely to the fact that they are usually strongly damped or aperiodic impulses. When such an impulse is im-

pressed on a tuned circuit it tends to excite 55 oscillations in this circuit, irrespective of the frequency to which it is tuned, and such shock oscillations produce a disturbing effect on the receiver. The purpose of the present invention is to prevent the production of such shock oscillations and the transmission of disturbing impulses to the receiving system. This is preferably accomplished 60 by making at least a part of the receiving system with sufficient damping to prevent 65 the setting up of free oscillations therein, and, it may be, also by coupling such part of the receiving system to the remainder of the system by a coupling sufficiently loose to prevent the transmission of such strongly 70 damped currents as may be excited by powerful aperiodic or strongly damped strays.

In Figure 1 of the drawing, which shows a simple embodiment of the invention, A is a collecting element which is here shown 75 as an ordinary antenna, B is a loading or tuning coil, and E is a receiver circuit inductively connected to the collecting circuit by a transformer $p_1 s_1$. The receiver circuit E includes a detector D, which is shown as 80 an electrostatic telephone serving also in a tuning capacity. The electrostatic detector D is excited by a sustained oscillation, of slightly different frequency from the sustained signal oscillation, produced by a local 85 oscillator or generator G coupled to the receiver circuit by a transformer $p_2 s_2$. The connection between the receiver circuit E and the antenna A includes baffle elements T, T₁, T₂, T₂', T₃, T₃', T₄, T₄', each comprising 90 an inductance L and capacity C, and each tuned to the signal frequency. A plurality of electrolytic cells or other intensity selective devices S₁, S₂ and S₃ are shunted across the baffle elements at a₁ b₁, a₂ b₂ and 95 a₃ b₃, these points being points of small potential difference for the signal impulses but relatively large potential difference for strays or foreign impulses. An oscillation transformer $p_3 s_3$ couples the baffle circuit to 100 the receiver circuit E. Each cell S₁, etc., is so designed and constructed as to offer free passage to impulses beyond a given intensity applied to its terminals, while excluding weaker impulses. Powerful strays 105 picked up by the antenna are thus shunted through the cell S₁ to the ground, and the residue shunted by the other selectors S₂

and S_3 , while the weaker signal impulses are excluded from the by-pass and find free passage through the baffle elements $T_1 T_1'$, etc., to the receiver circuit E , where they 5 are superimposed on the local oscillations of slightly different frequency produced by the generator G , thus producing beats which are detected by the amplifying detector D .

The baffle elements $T_1 T_1'$, etc., greatly increase 10 the effectiveness of the intensity selective devices S_1 , etc., because of their frequency selective property. Being tuned to the signal frequency their reactance to the signal impulses is zero, but their reactance 15 to any other frequency is high. The points $a_1 b_1$, etc., therefore will be points of small potential difference at the signal frequency, but of relatively large potential difference for any other frequency, or for aperiodic 20 impulses, which thus tend more strongly to escape through the by-pass. By this combination of an intensity selective device S_1 , etc., with a frequency selective device $T_1 T_1'$, etc., the effectiveness of the intensity selective device is greatly increased. It thus acts preferentially to divert from the receiver circuit not only strays that are stronger than 25 the signal impulses but may even divert strays that are much weaker than the signal impulses since such strays are impressed upon it with proportionately greater 30 intensity than the signal impulses.

The electrolytic cells or other intensity 35 selectors S_1 , S_2 , S_3 are made progressively sensitive. The first selector S_1 is made rugged so that it will not be injured by the most powerful atmosphere disturbances. This will divert in large measure the most 40 powerful strays. The residue which is not diverted but succeeds in passing the baffle elements $T_1 T_1'$ then encounters the baffle elements $T_2 T_2'$ and is diverted by the more sensitive selector S_2 , and this process may be repeated until the strays are practically 45 eliminated.

While the use of the baffle circuit or frequency selective device is thus highly desirable in connection with the intensity selective device, it is not essential and the apparatus 50 will be effective even though the cell shunts strong signal impulses to the same extent that it shunts strays. In such case weaker signal impulses, or the remnant of strong signal impulses which is not diverted, 55 will be amplified by the receiver so that they will produce a stronger signal than such remnant of the strays as may escape the by-pass and enter the receiving system. The baffle element is desirable, however, not only 60 to increase the effectiveness of the intensity selector, but also for an additional reason which I will explain.

When the local exciting current of a beats system is large with respect to the signal current, oscillations of considerable intensity

may escape through the transformer p, s . These oscillations, if applied to the cells S_1 , S_2 , etc., in full force, might be so powerful as to impair their effectiveness in diverting strays. By the use of the baffle elements 70 $T_1 T_1'$, etc., their effect on the intensity selectors may be reduced to any desired value, since the points $a_1 b_1$, etc., will then be points of small potential difference to the local oscillations as well as to the signal impulses, 75 the difference of frequency being small.

Preferably I employ the intensity selective device in connection with a receiving system having a baffle circuit offering but little impedance to the signal impulses but great 80 impedance to the strays, as I described in Letters Patent No. 1,315,584, dated September 9, 1919. It is also desirable, though not of course necessary, to utilize with the system a receiver operating on the beats principle owing to its inherent stray-reducing 85 power.

The invention is not limited to use with an amplifying detector, nor with the beats system of receiving, but it is also applicable 90 to other receiving systems, including receivers of damped oscillations from an ordinary spark oscillator. With such a sysstem it is usually desirable to employ a plurality of 95 intensity selectors, together with a plurality of baffle elements. Two examples of this type are shown in Figures 1 and 2. In the former I have illustrated a beats receiver; in the latter an ordinary receiver of damped oscillations, though either type of receiver 100 might be used in either arrangement.

Inasmuch as a powerful aperiodic or strongly damped stray may excite oscillations in a resonant circuit, irrespective of its frequency, at least a part of the receiving 105 system should be made with sufficient damping to prevent the setting up of free oscillations therein. Preferably the first baffle unit, which, in the arrangement shown, is the one directly associated with the collector, 110 should be so strongly damped as to be aperiodic and incapable of sustaining and transmitting free oscillations to the receiver circuit. Thus in Figure 1 that portion of the baffle system which comprises the baffle elements T_1 and T_1' is so constructed that it 115 cannot sustain prolonged free oscillations and it is coupled to the remainder of the system by a transformer $p_1 s_1$ whose coupling is sufficiently loose to prevent the transmission of such strongly damped currents as may escape the intensity selector S_1 . The requisite damping may be introduced by suitably proportioning the resistance and other energy consuming elements of the circuit with 120 respect to the reactive elements, or by other equivalent damping means. The damping of the circuit $T_1 T_1'$ and the loose coupling of the transformer $p_1 s_1$ should not however 125 be sufficient to obstruct the passage of the 130

more or less sustained signal impulses. To this end I prefer to get the requisite damping by diminishing the loading of the circuit rather than by increasing its resistance; 5 in other words, by making the circuit with relatively small self-induction and large capacity. The succeeding baffle elements T_2 , T_3 , etc., should be more heavily loaded in progressive sequence. An adjustable resistance R , or its equivalent, may be included in the baffle circuit $T_1 T_1'$ if desired to control its damping.

While I prefer to arrange the baffle elements symmetrically on opposite sides of the 15 receiving circuit, this is not necessary. The lower series of baffle elements may be omitted and each by-pass directly ground as indicated in Figure 2. Preferably, however, at least one baffle element T_4' , Figure 2, is retained 20 between the receiver circuit and ground, to eliminate any disturbances that might result if the ground connection had a considerable impedance. The receiver circuit shown in this figure comprises a detector D and the 25 usual tuning elements $C, s.$

The invention is not limited to the use of any particular form of intensity selective device, nor to the particular arrangement of apparatus shown, but is applicable to a great 30 variety of systems including equivalent means for preventing the production and transmission to the receiver of shock oscillations by the action of strays. The particular arrangement shown in the drawing is the 35 same as that shown and fully described in my said Patent No. 1,407,103 and its specific features, not forming an essential part of the invention sought to be covered in the present application, need not be described in 40 detail.

Having now described my invention and what I claim is new therein, what I desire to secure by Letters Patent is as follows:

1. In a receiving system for radiant energy, the combination with an antenna or collecting element, of a receiving apparatus and a tuned damping circuit, transmitting signal impulses freely to the receiving apparatus and including damping means for preventing excitation and transmission of free oscillations excited by strays, and an intensity selective device associated with the tuned damping circuit, substantially as set forth.
2. In a receiving system for radiant energy, the combination of a collecting element, a receiving apparatus associated therewith, means for preventing the excitation of shock oscillations in the collecting element, a baffle element affording free passage to the signal impulses but obstructing the flow of foreign impulses and strays, means acting preferentially to divert the energy of shock impulses from the baffle element, and means for transmitting signal os-

cillations from the collecting element to the receiving apparatus, substantially as set forth.

3. In a receiving system for radiant energy, the combination of a collecting element, a receiving apparatus associated therewith, means for preventing the excitation of shock oscillations in the collecting element, frequency selective means for transmitting signal oscillations from the collecting element to the receiving apparatus, and intensity selective means cooperating with the frequency selective means to divert preferentially the energy of shock impulses, substantially as set forth.

4. In a receiving system for radiant energy, the combination of a collecting element, a receiving apparatus, a baffle element tuned to signal frequency associated with the collecting element and the receiving apparatus, means for preventing the excitation of shock oscillations in the collecting element, means associated with the baffle element at points of small potential differences at signal frequency for diverting the energy of shock impulses, and means for transmitting signal oscillations from the collecting element to the receiving apparatus, substantially as set forth.

5. In a receiving system for radiant energy, the combination of an aperiodic circuit with associated collecting means, a baffle element tuned to signal frequency transmitting signal energy therefrom, means cooperating with the baffle element to preferentially divert and dissipate the energy of shock impulses, and means for receiving the energy of signal frequency.

6. In a receiving system for radiant energy, the combination of an aperiodic circuit with associated collecting means, a baffle element tuned to signal frequency transmitting signal energy therefrom, intensity selective means cooperating with the baffle element to preferentially divert and dissipate the energy of shock impulses, and means for receiving the energy of signal frequency.

7. In a receiving system for radiant energy, a collecting system incapable of sustaining and transmitting free shock oscillations, a baffle element, including balanced reactances, receiving signal energy therefrom, a by-pass shunting said baffle element containing means for dissipating stray energy, and means for receiving signal energy from the collecting system.

8. In a receiving system for radiant energy, a collecting system incapable of shock oscillations of signal frequency, an aperiodic baffle element, including balanced reactances and damping means, receiving signal energy therefrom, a by-pass shunting said baffle element containing means for dissipating stray energy, and means for receiving signal energy from the collecting system.

9. In a receiving system for radiant energy, a collector, a baffle element, including balanced reactances and damping means for preventing the excitation of shock oscillations therein, transmitting signal energy from the collector, energy dissipating means by-passing the baffle element, and means for receiving signal energy transmitted by the baffle element.
10. In a receiving system for radiant energy, a collector, a branched circuit receiving energy therefrom, one branch, comprising balanced reactances and damping means, transmitting signal energy, the other branch comprising means for dissipating stray energy, and signal receiving apparatus op-
11. In a receiving system for radiant energy, an aperiodic collector, a branched circuit receiving energy therefrom, one branch, comprising balanced reactances and damping means, transmitting signal energy, the other branch comprising means cooperating with the balanced reactances to operate preferentially on abrupt non-signal impulses, and signal receiving apparatus operated by signal energy transmitted by the balanced reactances.

This specification signed this 19th day of 30 January, A. D. 1922.

FREDERICK K. VREELAND.
